UNITED STATES PATENT OFFICE.

EDWIN J. ARMSTRONG, OF ERIE, PENNSYLVANIA.

GOVERNOR.

SPECIFICATION forming part of Letters Patent No. 700,004, dated May 13, 1902.

Application filed November 20, 1901. Serial No. 83,059. (No model.)

To all whom it may concern:

Be it known that I, EDWIN J. ARMSTRONG, a citizen of the United States, residing at Erie, in the county of Erie and State of Pennsylvania, have invented certain new and useful Improvements in Governors; and I do declare the following to be a full, clear, and exact description of the invention, such as will enable others skilled in the art to which it appertains

10 to make and use the same.

This invention relates generally to governors, and particularly to shaft-governors for steam-engines; and it has for its object to provide a shaft-governor of few parts, of simple 15 and inexpensive construction, not liable to derangement by wear, and which shall be capable of controlling the speed of the engine to which it is attached with a high degree of accuracy; and it consists of the parts and combinations of parts hereinafter described and claimed.

In the accompanying drawing, forming a part of this specification, is illustrated a side elevation of my improved governor.

25 The two primary requirements in a governor of this type are, first, that it should be balanced against the disturbing action of gravity, and, second, that friction should be reduced to a very small amount. These requirements are met and the object above named attained by the mechanism now to be described.

Referring to the drawing, A represents the shaft upon which the fly-wheel or carrier B is mounted. An eccentric C is mounted upon 35 a pivot *a* from the wheel or carrier and is adapted to be swung through a suitable arc thereon.

D is an arm extending laterally from the 40 eccentric and pivotally connected at its free end to the end of a link E, the other end of said link being pivotally connected to a weight F, mounted on the free end of a spring G, which is attached to the carrier or wheel.

45 The weight F is preferably made of such proportions that it will balance the eccentric C, together with the eccentric-strap and other parts which may be attached thereto.

The motion of the weight and eccentric being in opposite directions, it is apparent that the disturbing action of gravity which exists

where the movement of one part of a governor is not accompanied by a movement in the opposite direction of some other part of equal gravity moment is provided against. The 55 weight F being carried by the spring G and having its centrifugal force entirely resisted by said spring, none of the centrifugal force of said weight is transmitted through the pivots of the governor. Therefore the strains 60 upon said pivots are very small and not great enough to interfere with their proper lubrication or to cause serious wear.

The link E is so constructed as to be adjustable lengthwise, which while not essential to 65 the proper working of the governor affords a convenient adjustment for varying the positions, and consequently the centrifugal force, of the weight. As shown, the link E is composed of an internally-threaded member into 70 which an externally-threaded member screws, and a nut is employed to secure the parts in their adjusted position.

I am aware that a gravity-balance in shaft-governors is old in the patent to John E. 75 Sweet, No. 252,276, January 10, 1882, and that it is also old to mount a weight upon a spring so that the weight is both carried and its centrifugal force resisted by said spring, as shown by the patent to D. A. Woodbury, No. 107,746, 80 September 27, 1870, and I make no claim for such devices *per se*, but only to the means whereby the useful results obtained by the use of these two known devices are combined in the same governor, since the gravity-balance and the removal of strain from the pivots are both necessary to obtain the best results in a shaft-governor.

Having thus described my invention, what I claim as new, and desire to secure by Letters 90 Patent, is—

1. The combination in a shaft-governor of a carrier, an eccentric pivotally mounted thereon and adapted to be shifted through a suitable range, a centrifugal weight, a spring upon 95 which said weight is mounted and means whereby said weight and eccentric are so connected that their movements will be in opposite directions and of approximately equal gravity moment, thereby balancing the weight 100 of the eccentric, and also so that the centrifugal force exerted by the weight shall not

be transmitted through the pivots of the governor.

2. The combination in a shaft-governor of a carrier, an eccentric pivotally mounted thereon and adapted to be shifted through a suitable range, a centrifugally-acting weight, a spring upon which said weight is mounted, and a longitudinally-adjustable link connecting said eccentric and weight in such a man-

ner that their movements shall be in opposite to directions.

In testimony whereof I affix my signature in presence of two witnesses.

EDWIN J. ARMSTRONG.
